MOLDED PLASTIC CONTAINER

Harry M. Kikuchi, Cleveland, Ohio

Application June 5, 1953, Serial No. 359,920

2 Claims. (Cl. 150—37)

This invention relates as indicated to a molded plastic container, and more particularly to a container of a type suitable for employment as a coin purse, compact or the like.

A well-known form of coin purse comprises a flat pouch usually more or less semi-circular in shape and provided with a flexible flap or cover adapted to be folded over the pouch portion to close the opening of the latter. When such flap or cover is flexed to open position, it serves as a receptacle for coins which may now be permitted to slide out of the mouth of the pouch. Such flap or cover is ordinarily provided with a lip or flange to prevent escape of such coins and also to embrace the pouch portion when the purse is closed.

Purses and pouches of this type have generally been made of leather and, while very popular, have nevertheless had certain disadvantages. They are rather expensive for a small article of this nature and generally do not wear too well, like many leather articles frequently tending to come apart at the seams before the component parts are themselves worn out. Considerable hand work is involved in their manufacture.

It is accordingly a principal object of my invention to provide a purse or pouch of the general conformation indicated but molded in a single piece of flexible synthetic plastic.

Another object of my invention is to provide such molded plastic pouch or container which will close tightly and neatly and remain closed in a purse or pocket, yet be readily openable when desired.

Other objects of the invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a perspective view of my new plastic article in closed condition;

Fig. 2 is a perspective view of such article opened;

Fig. 3 is a longitudinal sectional view taken on the line 3—3 on Fig. 1;

Fig. 4 is a transverse sectional view taken on the line 4—4 on Fig. 3; and

Fig. 5 is a fragmentary sectional view taken through a portion of a gang mold showing the arrangement of the mold parts for the production of my new plastic purse or like article.

Referring now more particularly to Figs. 1—4 of the drawing, my new molded plastic pouch or purse generally resembles the leather coin purses previously known but differs therefrom in certain important respects. As indicated, it is molded in unitary form in a single piece of plastic material without any stitching or the like to come

2

apart in use. It may, moreover, be molded to quite close tolerances so that, when closed, the parts will fit tightly and tend to remain in closed position as well as preventing escape of the contents therefrom. A variety of flexible plastic materials may be employed in the manufacture of my new article including the well-known vinyl plastics, polyethylene and the like.

Such article in accordance with my invention comprises a pouch portion 1 and a tray portion 2 having an upstanding flange 3 adapted to embrace and grip the pouch portion 1 when the tray is folded to Fig. 1 position. The ends 4 and 5 of such flange 3 are spaced from the mouth of pouch 1 to leave an intervening portion 6 adapted to serve as a hinge and closure for the mouth of such pouch.

A tab 7 is molded as an extension of the base portion of pouch 1 at the end opposite to hinge 6 and is provided with an aperture 8 therethrough to permit the article to be attached to a key chain or the like. The lip of flange 3 may desirably be notched at 9 to receive such tab 7 in closely fitting and gripping engagement when the pouch is closed as shown in Figs. 1 and 3. Inasmuch as these plastic materials have a fairly high coefficient of friction, this arrangement assists in securing the article tightly closed. The tab 7 nevertheless affords a convenient grip for the thumb and forefinger, facilitating opening of the pouch when desired.

A small aperture 10 may also be provided through the end wall of pouch portion 1 adjacent tab 7 to prevent formation of a vacuum when withdrawing the molded article from the mold as described below, and also to serve as auxiliary latching means in combination with a small lug or protuberance 11 formed on the inner face of flange 3 in position to interengage with such hole 10 when the article is folded to closed position (Fig. 3).

As best shown in Fig. 2, the wall 12 of pouch portion 1 will be slightly inset at 13 relative to wall or flange 3 of tray portion 2 so that when the article is folded to closed position, such flange 3 will tightly but precisely fit the outside of wall 12 without appreciable distortion.

Now referring more particularly to Fig. 5 of the drawing, it will be seen that the portion of a plastic injection gang mold there shown is designed to mold the article in unitary form. The hole 8 in tab 7 will, however, be punched out after the article has been molded. Three mold parts 14, 15 and 16 are shown, parts 14 and 16 being secured together and defining the outer surfaces of the molded article and part 15 being a withdrawable insert. Part 15 defines the interior of the article, both pouch and tray, extension 17 defining the interior of the pouch 1. In this case the pouch portion is shaped to permit withdrawal of such extension from the cavity defined by parts 14 and 16. The plastic material is intruded through a sprue 18. When the mold is opened, it will be seen that part 15 may then be withdrawn to remove portion 17 from the pouch 1 of the molded article. Such article may then be stripped from the mold.

The mold thus employed is relatively simple and inexpensive of construction and facilitates stripping of the finished articles. Due to having been molded in open recurved form as shown in Fig. 5 (the tray and pouch being at right angles) the purse is easily opened from Fig. 1 to Fig. 2 position, but nevertheless will stay closed in the pocket due to frictional engagement of the parts and the grip of notch 9 on tab 7 and/or the engagement of lug 11 in aperture 10.

The finished article may be employed for a variety of purposes such as a lady's compact or as a lens case as well as for the more usual purpose of a container for small coins.

Other modes of applying the principle of the invention may be employed, change being made as regards the de-

tails described, provided the features stated in any of the following claims or the equivalent of such be employed.

I therefore particularly point out and distinctly claim as my invention:

1. A molded flexible plastic pouch having a tray portion integral therewith adapted to project outwardly from the mouth of said pouch and comprising an extension of one side of said pouch, said pouch comprising two generally parallel side portions joined by an arcuate wall portion, a flange on said tray about the edge thereof projecting generally normal thereto and adapted snugly to embrace said pouch wall portion when said tray is flexed against the latter, the ends of said flange being spaced from the mouth of said pouch and said flange following an arcuate contour corresponding to that of the outer side of said pouch wall portion to enable it thus snugly to embrace the latter, a tab extending from the end of said pouch opposite to the mouth thereof, the portion of the free edge of said flange which is opposed thereto in closed position being notched and dimensioned to receive and laterally frictionally to grip said tab, and a small lug raised on the inner side of said flange adjacent such notch, said pouch wall portion adjacent said tab having a small aperture therein positioned to engage said lug.

2. A molded flexible plastic pouch having a tray portion integral therewith adapted to project outwardly from

the mouth of said pouch and comprising an extension of one side of said pouch, said pouch comprising two generally parallel side portions joined by an arcuate wall portion, a flange on said tray about the edge thereof projecting generally normal thereto and adapted snugly to embrace said pouch wall portion when said tray is flexed against the latter, the ends of said flange being spaced from the mouth of said pouch and said flange following an arcuate contour corresponding to that of the outer side of said pouch wall portion to enable it thus snugly to embrace the latter, and a tab extending from the end of said pouch opposite to the mouth thereof, the portion of the free edge of said flange which is opposed thereto in closed position being notched and dimensioned to receive and laterally frictionally to grip said tab.
